UNITED STATES PATENT OFFICE.

CHARLES H. DOME, OF ENID, OKLAHOMA TERRITORY.

BUTTON-ATTACHING DEVICE.

No. 867,352.

Specification of Letters Patent.

Patented Oct. 1, 1907.

Application filed January 7, 1907. Serial No. 351,186.

To all whom it may concern:

Be it known that I, CHARLES H. DOME, a citizen of the United States, residing at Enid, in the county of Garfield, Oklahoma Territory, have invented certain new and useful Improvements in Button-Attaching Devices; and I do declare the following to be a full, clear, and exact description of the invention, such as will enable others skilled in the art to which it appertains to make and use the same.

- 10 My invention has relation to new and useful improvements in button attaching devices, and has for its object to provide a button with simple means whereby it may be removably secured or attached to a piece of cloth or like material at a moment's notice.
- 15 With these ends in view, my invention consists in the novel construction, combination and arrangement of parts as illustrated in the drawings and set forth in the specification and claims hereunto appended.

In the accompanying drawings, in which like parts 20 are designated by like characters throughout the several views,—Figure 1 is a front face view of my invention attached to a piece of cloth with a button secured in place; Fig. 2 is a perspective of my invention; and Fig. 3 a sectional view on the line 3—3 of 25 Fig. 1. Fig. 4 is a central longitudinal section, taken on the line 4—4 of Fig. 1, looking in the direction of the arrow, and showing the button in elevation.

My invention is described as follows,—The numeral 1 represents a clamping plate. Said plate is of preferably rectangular form, terminates at its inner edge 30 in a number of inwardly-extending teeth 2 and is provided at each side edge with a longitudinal, inwardly-extending flange 3, having a transverse perforation 4 near its inner end and an engaging ear or catch 5 near or at its opposite end. In the application of my invention, a button 6 is secured to the outer face of said clamping plate 1. If found desirable, said plate may have a number of eyes or perforations in its central part and the button sewed thereto. Said clamping plate 1 is pivotally connected at its inner end to a metallic frame 7, comprising inwardly-extending arms 8, parallel side wires 9 and an inner horizontal wire 10 connecting the inner ends of the lowermost of

said parallel side wires 9. The catches or engaging ears 5, located near the ends of the longitudinal, inwardly-extending flanges 3 of the clamping plate, engage respectively between the adjacent pairs of parallel side wires 9 of said metallic frame 7, and hold said clamping plate in clamping position, the side portions of the frame being adapted to spring apart to permit engagement of the catches therewith. In the application of my invention, it is attached or secured to a piece of cloth or like material by passing the same between the parallel side wires of said frame, when the said inwardly-extending teeth of said clamping plate 1 engage the cloth or other material and hold my button attaching device in place. My invention may be detached from the cloth or other material to which it is secured by pressing on the same back of the button, which releases the catches 5 from engagement with the parallel side wires of said frame when the clamping plate 1 may be swung inwardly, releasing the teeth 2 thereof from engagement with the cloth.

Having thus described my invention, what I claim 65 as new, and desire to secure by Letters-Patent,—

1. In a button attaching device, the combination of a clamping plate having inwardly-extending teeth at its inner edge, an inwardly-extending longitudinal flange having a transverse perforation and catch at each of its side edges, and a frame comprising inwardly-extending arms, parallel side wires, and an inner horizontal wire, substantially as described.
2. In a button attaching device, a frame presenting two pairs of parallel spaced side portions, one pair of said portions being provided with inwardly projecting arms, and the other pair connected by an end bar, a clamping plate pivoted on said inwardly extending arms and provided at its inner end with sharpened engaging teeth, said plate having side flanges bent adjacent their outer ends to form catches for engagement between the respective pairs of side portions, and a button attached to the clamping plate.

In testimony whereof I have hereunto set my hand in presence of two subscribing witnesses.

CHARLES H. DOME.
